MUSIC RACK

Leta Wallace, Kansas City, Mo.

Application October 24, 1936, Serial No. 107,452

8 Claims. (Cl. 45—82)

My invention relates to music racks and more particularly to auxiliary music racks for pianos.

The music rests provided on the music desks of pianos are primarily designed for adults. Children and near sighted persons have difficulty in using the music rests provided. There is a tendency to lean forward, thus causing a particularly unfavorable condition. Not only is the position at the piano improper but in leaning forward and looking upwardly an undue amount of energy is necessary, inducing fatigue and early robbing the child of its ability to concentrate at the music lesson. The correct distance of music from the player's eyes should be sixteen inches.

One object of my invention is to provide a music rack which can be adapted to the music rest of the music desk on all pianos, including both the grand piano type and the upright piano type.

Another object of my invention is to provide a music rest which is light in weight, can be easily adjusted and will not scratch or injure the piano.

Other and further objects of my invention will appear from the following description.

In the accompanying drawings, which form part of the instant specification and are to be read in conjunction therewith and in which like reference numerals are used to indicate like parts in the various views.

Figure 1 is a fragmentary elevation of a grand piano showing my music rack in place.

Figure 2 is a sectional elevation of the music rack shown in Figure 1.

Figure 3 is a sectional view of a portion of my music rack showing the music rest in one adjusted position.

Figure 4 is a sectional view similar to that of Figure 3 showing the music rest in another adjusted position.

Figure 5 is a perspective view of a portion of my assembly.

Figure 6 is a perspective view of a detail.

Figure 7 is an enlarged sectional view of a detail.

Figure 8 is an enlarged fragmentary elevation of a detail.

Figure 9 is an elevation of a portion of an upright piano showing my music rack attached thereto.

Figure 10 is a side view partly in section of the arrangement shown in Figure 9.

Figure 11 is an elevation on an enlarged scale of a portion of the assembly used on upright pianos.

Figure 12 is a sectional view taken on the line 12—12 of Figure 11.

In general my invention contemplates the provision of a supporting means adapted to clamp upon the music rack of the piano and at once acts as a support for the auxiliary music rack proper and as a bracing means for the piano music rack. Means are provided for adjusting the auxiliary music rack as to height, distance from the user and also as to angle.

More particularly referring now to the drawings, the music desk of a grand piano usually comprises a member 1 pivoted at 2 so that it is adapted to assume the position shown in Figure 2 when erected. When not in use the music rest 1 is adapted to be pivoted around the hinge 2 so that the upper end will move to the left as viewed in Figure 2, that is toward the front of the piano. The supporting member 3 is then adapted to slide backwardly to closed position. There is also provided a stringer 4 against which the lower edge of the music rests. The music racks 1 on various pianos are of different heights. The height of the music rack above the keys on different pianos is different and the support upon which the music rack 1 is pivoted likewise is differently positioned and has different amplitudes of motion. Furthermore, the angle which the music rest 1 assumes when in erected position is different on different pianos.

For grand pianos my music rack comprises a board 5 to which is hinged connected a member 6. Member 6 is provided with a groove 7 in which the tongue 8 of clamp member 9 is adapted to ride. An auxiliary clamping member 10 may be provided. The pivotal connection between members 5 and 6 may be by means of flexible material 11 glued or otherwise secured to both members 5 and 6. The back of members 5 and 6 may be covered by felt 12 to prevent scratching the music rest of the piano. In use the clamping assembly is clamped over the top of the music rest of the piano by means of a clamping bolt 13 with the lower end of board 5 positioned against the stringer 4 as can readily be seen by reference to Figure 2. In this position the board 5 will act as a brace preventing the music rest of the piano from pivoting around its hinge 2. The board 5 also acts as a support upon which the auxiliary music rack is adjustably mounted as will herein- after more fully be pointed out.

Referring now to Figure 6 there is shown a bracket. One end 14 of the bracket 15 is adapted to embrace the board 5 as can readily be seen by reference to Figures 3 and 4. To the arms 16 55

of the bracket I secure the auxiliary music rest proper 17, by means of a clamp bolt 18. Clamped between the arm 16 and the music rest 17 are a pair of wedges 19 and 20 through which the angle of clamping can be readily adjusted. It will be observed that if both narrow portions of the wedges are downwardly the angle between the brackets 16 and the plane of the music rest 17 will be less than 90°, as shown in full lines in Figure 2. By positioning one thin end upwardly and one thin end downwardly the angle can be made to be 90°, as shown in dotted lines in Figure 2 and in full lines in Figure 7. By placing both butt ends of the wedges together and positioning them downwardly, the angle between the bracket 16 and the plane of the music rest 17 can be made greater than 90°. It will be observed by intermediate positioning of the wedges, any desired angle between the limits of the wedges can be achieved. Likewise, different angles can be obtained by using only one of the two wedges or by using wedges having different angles. In this manner a simple adjustment to obtain the desired angle for the music rest 17 is achieved. The bracket 15 is made of malleable metal and the arm 16 of the bracket is secured to the music rest 17 through slots 21.

Referring now to Figure 3 it will be noted that the distance between end 14 of the bracket and the music rest 17 is greater than this distance in Figure 4, thus providing an adjustment of distance of the music rest from the board 5 to enable the music rest to be used on pianos having various distances from the music rest 1 provided and the fall board 22 of the piano. This adjustment is made by simply bending the arm 16 of the bracket outwardly, sliding the clamping bolts 18 along the slots 21.

It will be observed by reference to Figure 2 that the weight of the bracket and the music rest 17 tends to rotate the bracket counterclockwise. This will bring the upper rear edges of the inside of the embracing end 14 of the bracket and the lower inside edge of the end 14 against the rear and forward sides of the board 5, respectively, exerting a clamping action. It will be observed that this clamping action will be increased as the weight of music upon the music rest 17 is increased. The friction exerted by this clamping action is sufficient to carry the weight of any music which can be placed upon the support ledge 23 of the music rack 17. The height of the music can then be readily adjusted by simply moving the bracket up and down and upon being released it will remain in the position placed. This ready adjustment of height enables the instructor to move the music up and down for the pupil to bring a desired line of a page in proper position.

Referring now to Figures 9, 10, 11 and 12 of the drawings, there is shown a modification of my invention when used upon upright pianos. In this type of piano the music rest usually comprises a pivoted panel 24 which is always a greater depth than the music rest 1 provided upon grand pianos. The same principles, however, are involved, namely, to prevent the music rest 24 from pivoting around its axis 25 and to permit the bracing means to act as a support for an auxiliary music rest. The same auxiliary music rest 70 is used. The support comprises an elongated member 26, carrying a bracket 27 at its upper end. The bracket is provided with an adjustable clamp 28. The member 26 is provided with a slot 29 in which a board 30, similar to board 5, is adapted to be adjustably positioned by means

of a clamping bolt 31. In this manner various heights can be readily accommodated. The upper end of the member 26 is clamped to the upper end of the music rest 24 by means of the clamp 28. The music rest is moved to open position, as shown in Figure 10, and the lower end of the board 30 is placed against the stringer 32 of the piano. The clamping bolt 31 is then clamped to the music rack 17 and its bracket with embracing end 14 is positioned upon the board 30 precisely in the same manner as upon board 5; board 30 and board 5 being made of the same weight and thickness.

It will be observed that I have accomplished the objects of my invention. I have provided an adjustable auxiliary music rack which may be used upon all makes of grand and upright pianos. The construction is such that it will not scratch the piano, is light in weight, is easily adjusted and will provide a music rack which will enable children to have the music properly positioned, thus avoiding nervous strain and fatigue occasioned by improperly positioned music.

It will be understood that certain features and sub-combinations are of utility and may be employed without reference to other features and sub-combinations. This is contemplated by and is within the scope of my claims. It is further obvious that various changes may be made in details within the scope of my claims without departing from the spirit of my invention. It is, therefore, to be understood that my invention is not to be limited to the specific details shown and described.

Having thus described my invention, what I claim is:

1. An auxiliary music rack adapted to be used in connection with the music rest of a piano, a brace member, means for clamping said brace member to the music rack of a piano, said brace member extending from said clamp at an angle to said rest and engaging a part of the piano to prevent said rest from pivoting, a support carried by said brace member and an auxiliary music rack carried by said support.

2. In combination with the music rack of a piano an auxiliary music rest comprising a combined bracing and supporting member, a clamp for clamping said member to said piano music rack, said combined bracing and supporting member extending from said clamp to an angle to said rack for engaging a part of the piano to prevent said rack from pivoting, a bracket adjustably carried by said bracing member, an auxiliary music rest supported by said bracket and means for adjusting said music rest on said bracket.

3. An auxiliary music rest adapted to be used in connection with the music rack of a piano, a combined bracing and supporting member, means for clamping said member to the music rack of a piano, said combined bracing and supporting member extending from said clamping means at an angle to said rack and engaging a part of the piano to prevent said rack from pivoting, a bracket, means for adjustably positioning said bracket on said combined bracing and supporting member, an auxiliary music rest supported by said bracket, and means for adjusting said auxiliary music rest to positions whereby said auxiliary music rest will occupy planes forming various angles with the plane of the music rack of the piano.

4. An auxiliary music rest adapted to be used in connection with the music rack of a piano, a combined bracing and supporting member, means

for clamping said member to the music rack of a piano, said combined bracing and supporting member extending from said clamping means at an angle to said rack and engaging a part of the piano to prevent the rack from pivoting, a bracket, means for adjustably positioning said bracket on said combined bracing and supporting member, an auxiliary music rest supported by said bracket, means for adjusting said auxiliary music rest to positions whereby said auxiliary music rest will occupy planes forming various angles with the plane of the music rack of the piano, and means for adjusting said auxiliary music rack to planes lying at different distances from the plane of the music rack of the piano.

5. An auxiliary music rest as in claim 3, wherein said means for angularly adjusting said auxiliary music rest comprises means for clamping said music rest to said bracket and wedges adjustably positioned between said bracket and said music rest.

10. An auxiliary music rest as in claim 4, where-

in said means for positioning said music rest at different distances from the music rack of the piano comprises slots in said music rest whereby said bracket may be bent to present various normal distances between said music rest and music rack.

15. A music rest as is claim 3, wherein said means for clamping said bracing means is pivotally connected to said bracing means and said clamping means is longitudinally adjustable to enable it to be used on piano music racks of various heights.

8. A music rest as in claim 2, wherein said means for adjustably positioning said bracket upon said combined bracing and supporting means comprises bracket portions at least partially surrounding said supporting means, with sufficient clearance whereby said bracket is adapted to rotate about a horizontal axis lying substantially in the plane of said bracing member, to frictionally clamp said supporting means between front and rear portions of said bracing means.

LETA WALLACE.
